(57) **CLAIM**

The ornamental design for bottle, as shown and described.

DESCRIPTION

FIG. 1 is a front perspective view of my bottle in accordance with my new design;

FIG. 2 is a front view thereof, with rear, left-side elevational and right side elevational views being identical; and,

FIG. 3 is a top plan view thereof.

The bottom plan view of the bottle is not shown in the drawings or described in the specification and, therefore, forms no part of the claimed design.
